UNITED STATES PATENT OFFICE.

JOSEPH J. BALK, OF BUFFALO, NEW YORK, ASSIGNOR TO MARKEL ELECTRIC PRODUCTS, INC., OF BUFFALO, NEW YORK, A CORPORATION OF NEW YORK.

DESIGN FOR A BENCH STANDARD.

Application filed November 23, 1928. Serial No. 29,009. Term of patent 3½ years.

To all whom it may concern:

Be it known that I, JOSEPH J. BALK, a citizen of the United States, residing at Buffalo, in the county of Erie and State of New York, have invented a new, original, and ornamental Design for Bench Standards, of which the following is a specification, reference being had to the accompanying drawing, forming part thereof.

In said drawing:

Figure 1 is a side elevation of a bench standard embodying my new design. In this figure half of the design is shown in full lines and the remaining half in outline in dot and dash lines, the pattern being repeated.

Figure 2 is a top plan view of the same.

I claim:

The ornamental design for a bench standard, substantially as shown and described.

JOSEPH J. BALK.
